(57) **CLAIM**

The ornamental design for an adapter ring, as shown.

DESCRIPTION

FIG. 1 is an elevated, perspective view of a bottom of an adapter ring in accordance with an embodiment of my invention;

FIG. 2 is an elevated, perspective view of a top of the adapter ring;

FIG. 3 is a bottom plan view of the adapter ring;

FIG. 4 is a top plan view of the adapter ring; and,

FIG. 5 is a side view of the adapter ring, an opposing side view being a mirror image thereof.

The broken line showing is included for the purpose of illustrating portions of the article that form no part of the claimed design.
